INCANDESCENT IGNITION DEVICE

Application filed July 25, 1930. Serial No. 470,556.

This invention relates to improvements in incandescent ignition devices for electrically operated and controlled forced draft domestic fluid fuel burning mechanisms and more particularly to means for maintaining the ignition device incandescent when subjected to the cooling influence of the forced draft passing thereover.

In fluid fuel burners employing the so-called hot wire ignition device, it is common practice to provide a preheating time by passing the ignition circuit through the device to bring it to incandescence before the motor circuit is closed to supply the fluid fuel which in passing over or about the incandescent igniter is ignited thereby. It is obvious that the ignited must be adjacent the fluid fuel as it is supplied by the burner mechanism. It is also common practice to employ an ignition circuit of only sufficient current to heat the ignition device in passing therethrough to incandescence.

In fluid fuel burning mechanism of the forced draft type, it is common practice to cause the motor which supplies the fuel to the ignition device to also at the same time supply air under pressure to mix with the ignited fuel to insure more complete combustion. This forced draft is not only initiated as the fuel supply is initiated but also passes over the ignition device, so that a hot wire type of ignition device that has been heated to incandescence is subjected to the cooling effect of the forced draft passing thereover.

It has been found that in certain commercial fluid fuel burner mechanisms of the forced draft type that a hot wire ignition device that has been preheated by the passage of a current of sufficient voltage to make it incandescent during the preheating period, will be reduced in temperature by the forced draft to such an extent it will not remain hot enough to ignite the fluid fuel. It has also been found that if the current of the ignition circuit is increased sufficiently to maintain the ignition device incandescent under the cooling influence of certain forced drafts such current passing through the igniter during the preheating period, before the forced draft is initiated, is so great that it will cause

the ignition device to deteriorate, disintegrate, be consumed and become inoperative.

The object of this invention is to provide means that will automatically control the current of the ignition circuit so that when it is desired to operate the burner mechanism the current will be of such strength to bring the ignition device to incandescence without harm to it during the preheating period and then as the fuel and additional air under pressure are passed over the device the current is at the same time increased sufficiently to maintain the device incandescent to insure ignition of the fuel.

With these and other objects in view reference is made to the accompanying sheets of drawings, which illustrate preferred forms of this invention, with the understanding that minor detail changes may be made without departing from the scope thereof.

In the drawings:

Figure 1 is a view of a control unit, in front elevation with the cover removed, illustrating an embodiment of this invention.

Figure 2 is a diagrammatical view illustrating an installation of a fluid fuel burner in connection with a domestic heater installed with the control illustrated in Figure 1, and showing a wiring diagram of the electrical connections and controls employed with the burner mechanism illustrated.

Figure 3 is a view in horizontal central section of a draft pipe of a fluid fuel burner mechanism, illustrating the burner assembly in top plan view and illustrating a modified form of this invention.

Figure 4 is a view in transverse vertical section taken on the line 4-4 of Figure 3 looking in the direction of the arrows.

Figure 5 is a detail view in front elevation of the switch carrier plate employed in Figures 3 and 4.

As above stated, this invention relates to means whereby an incandescent igniter employed in connection with a forced draft or gun type domestic fluid fuel burner may be brought to incandescence before the forced draft passes thereover and maintained at incandescence while the forced draft is passed thereover, without detriment to or deteriora-

60

tion of the igniting device. This invention may, therefore, be applied to various types of constant current incandescent ignition devices and various types of controls may be employed therewith.

Figures 1 and 2 illustrate a commercial type of control with a commercial type of fluid fuel domestic burner mechanism to which this invention has been added, it being understood that the applicant does not restrict himself to the particular controls and mechanism referred to as being of commercial design.

Figure 1 illustrates a commercial type of constant current transformer actuated control adapted to be installed in the control system of an electrically operated fluid fuel burner mechanism, such as disclosed in the applicant's prior copending application, Serial #446,573, filed April 23, 1930, which embodies the improvements carried out in the further development of this particular control, as illustrated in the applicant's copending application Serial #465,882, filed July 7, 1930. This particular control is illustrated in the diagrammatical view in Figure 2 as connected in the control system. Referring to Figure 2, a fluid fuel burner mechanism 1 of commercial type is shown installed in connection with a domestic heater 2 of commercial type. The burner mechanism 1 is diagrammatically illustrated as being of the forced draft or gun type which is well recognized in this art and, therefore, it is not thought necessary to describe the construction and operation of this mechanism, other than the statement that it is operated by an electric motor 3, which motor creates a forced draft through the draft pipe 4 and at the same time supplies fluid fuel through a fuel pipe 5 arranged centrally within the draft pipe to discharge the fluid fuel through a nozzle arranged within the open end of the draft pipe within the domestic heater. In burners of this type, the ignition devices are customarily mounted upon the fuel pipe and the fuel pipe nozzle and ignition device is termed the burner assembly. The ignition device shown in Figure 2 comprises an incandescent igniter 6 such as disclosed in the applicant's prior copending applications Serial No. 331,542, filed January 10, 1930, and Serial No. 441,143, filed April 2, 1930.

The control device, illustrated in detail in Figure 1, is mounted upon panel 7, and includes a motor switch 8 normally opened and ignition switch 9 normally closed, a holding magnet 10 normally deenergized, and also discloses a constant current transformer including a floating primary coil 11 and stationary secondary coil 12 mounted within a rectangular core 13 with the stationary secondary coil resting upon the lower interior

side thereof and the primary coil adapted to float thereabove.

Referring to the wiring diagram in Figure 2, it is seen that the commercial current enters through a wire 14 passes through a commercial boiler control B, normally closed, and from thence through a commercial room thermostat T to a binding post upon the control panel 7 and after passing through the various switches and coils on the control panel, the commercial current returns from another binding post upon the panel 7 through the wire 15 to the commercial line.

As disclosed in said prior copending applications Serial No. 446,573, filed April 23, 1930, and No. 465,882 filed July 7, 1930, when the room thermostat calls for heat, by closing the circuit to the control panel, the commercial current passes first through the normally closed ignition switch 9, the primary coil 11 of the constant current transformer, and back to the commercial line, thereby energizing the secondary coil 12 of the constant current transformer. This coil 12 is connected by wire 16 to convey the secondary current through the incandescent igniting element 6 and back to the other terminal of said coil. As disclosed in said prior copending applications Serial No. 446,573, filed April 23, 1930, and No. 465,882, filed July 7, 1930, the energizing of the secondary coil 12 of the constant current transformer sets certain mechanism on the control panel into operation to first close the motor switch 8 and then open the ignition switch 9, whereby the commercial current from line 14 thereafter passes through said motor switch 8 and burner motor 3 back to the panel binding post connected with the return lead 15 to the commercial source of electricity. The starting of the motor initiates the draft thereafter forced through the draft pipe 4 and at the same time delivers fluid fuel through the nozzle adjacent the ignition device 6. As described in said prior copending application, the heat generated within the domestic heater 2 by the ignition of the fluid fuel acts upon a normally open combustion responsive switch S, causing same to close whereby the incoming commercial current passes from the binding post on the panel 7 by the wire S' through said switch and from thence through the coils of holding magnet 10 to the binding post of the return lead to the commercial source of electricity, whereby the motor switch is locked in closed position and the ignition switch is held in open position, so that after the ignition of the fluid fuel the secondary current passing through the igniter element 6 is discontinued.

The above is a description of a commercial control system for a fluid burner and the normal operation in starting the mechanism has been described. This invention contemplates the addition to the ignition circuit of an incandescent igniter of means whereby the

current passing through the incandescent igniter may be augmented as the burner motor initiates the draft which it thereafter, during normal operation, forces through the draft pipe and over the ignition element. As shown in Figures 1 and 2 a resistance element 17 is placed in the ignition circuit of the incandescent igniter and is preferably contained within the casing 18 mounted upon the top of the control panel 7 and, if desirable, is provided with a fuse or cut-out 19, as shown. This resistance element is connected by wire 20 in parallel with the wires 16 of the secondary circuit which, when energized, passes through the igniter 6. This resistance circuit 20 includes a normally closed switch 21 which is shown in Figure 1 of the drawing as being mounted upon the same support as the normally open motor switch 8 so that when the motor switch 8 is closed the resistance switch 21 will be opened.

As heretofore stated, this invention forms a part of the ignition system of an incandescent ignition device employed in a forced draft or gun type of fluid fuel burner, in which the igniter must necessarily be adjacent the discharge of the fuel pipe and, therefore, subjected to the cooling influence of the forced draft passing thereover while the fuel is ignited and during combustion. Under normal conditions, ordinarily the current of the secondary current is only sufficient to preheat or bring the igniter member to incandescence prior to the operation of the motor and will not be sufficient to continue the igniter in an incandescent condition during the passage of the forced draft thereover. If the current of the ignition device was of sufficient strength to maintain the igniter in an incandescent state after the forced draft began passing thereover, it would be of sufficient strength during the preheating stage prior to the passage of the forced draft to cause the igniting member to deteriorate or be consumed. Different types of forced draft burners employ different intensities of drafts so that the cooling effect upon a normally incandescent igniter would vary. It is, therefore, desirable to adjust the resistance 17 so that when the room thermostat calls for heat the secondary circuit set up through the wires 16, in which the normally closed resistance switch 21 and resistance element 17 are connected in parallel through the wires 20, will be such that the igniter 6 through the preheating period will become incandescent and when the motor switch 8 is closed and the resistance switch 21 opened the full strength of the current in the secondary circuit passing through the igniter will then be sufficient to maintain the igniter in an incandescent state until ignition of the fuel occurs or until the secondary circuit is broken.

As heretofore stated, this invention is not restricted to use in connection with the par-

ticular control illustrated in Figure 1. Some types of forced draft domestic fluid fuel burners employ a damper in the draft pipe, which is swung about a horizontal axis by the passage of the forced draft through the draft pipe. Another embodiment of this invention is illustrated in Figures 3, 4 and 5 which illustrate its application to this type of damper equipped forced draft burner mechanism. Figures 3 and 4 illustrate a damper 22 within the draft pipe 4 mounted to swing upon the horizontal pivot shaft 23, mounted in bearings secured to the interior of the draft pipe 4. One end of the pivot shaft 23 extends through a side of the draft pipe and carries upon its exterior end a switch carrier plate 24 upon which the resistance switch 21 is mounted. The exterior of the draft pipe is preferably provided with stops 25 so arranged that when the motor is idle and the damper 22 normally assumes a vertical position, the switch carrier plate 24 will contact one of the stops and will mount the resistance switch 21 in closed position. As soon as the motor starts and the forced draft passes through draft pipe 4 the damper 22 will be swung about its pivot by the impetus of the air passing through the draft pipe and carried to a horizontal position and maintained in that position during the operation of the motor. As the damper 22 swings into the horizontal position the carrier plate 24 will rotate the ignition switch 21 and swing it into open position, as illustrated in dotted lines on Figure 5. It is preferable to arrange the other stop 25 to engage the carrier plate 24 to prevent a further rotation of the ignition switch 21. In this form it is preferable to provide a cover 26 about the carrier plate and resistance switch, which may be secured to the side of the draft pipe, as shown in Figure 4. It is to be understood that the wires 20 leading from the resistance switch 21 are connected through a resistance element 17, as heretofore described and in parallel to the ignition circuit of the incandescent igniter 6.

What I claim is:

1. In an incandescent ignition device, an ignition circuit, an igniter in said circuit adapted to be brought to incandescence by the passage of the current of the ignition circuit therethrough, and means to vary the current of the ignition circuit to maintain a current sufficient to bring the igniter to incandescence during the preheating period and increase the current during the active ignition period.

2. An ignition device for an electrically operated fluid fuel burner mechanism of the forced draft type including a constant current transformer in the ignition circuit, an igniter in circuit with the constant current side of the transformer and in the path of the forced draft, and means for supplying a current in the ignition circuit sufficient to bring the igniter to incandescence prior to the ini-

tiation of the forced draft, and increase the strength of said current after the initiation of said forced draft.

3. A hot wire ignition device for an electrically actuated forced draft fluid fuel burner mechanism including a constant current transformer in the ignition circuit, an igniter in circuit with the constant current side of the transformer and in the path of the forced draft, and means for supplying a current sufficient to bring the igniter to incandescence prior to the starting of the burner motor and for increasing the said current sufficiently to maintain the igniter incandescent during the passage of the forced draft thereover.

4. A hot wire ignition device for an electrically actuated forced draft fluid fuel burner mechanism including a constant current transformer in the ignition circuit, an igniter in circuit with the constant current side of the transformer in the path of the forced draft, and means included in the ignition circuit for supplying a current sufficient to bring the igniter to incandescency prior to the initiation of the forced draft, and for increasing the said current sufficiently to maintain the igniter incandescent during the passage of the forced draft thereover.

5. A hot wire ignition device for an electrically actuated forced draft fluid fuel burner mechanism including a constant current transformer in the ignition circuit, an igniter in circuit with the constant current side of the transformer in the path of the forced draft, means included in the ignition circuit for supplying a current sufficient to bring the igniter to incandescency prior to the initiation of the forced draft, and means actuated by the initiation of operation of the burner motor for increasing the said current sufficiently to maintain the igniter incandescent during the passage of the forced draft thereover.

6. A hot wire ignition device for an electrically actuated forced draft fluid fuel burner mechanism including a constant current transformer in the ignition circuit, an igniter in circuit with the constant current side of the transformer in the path of the forced draft, means, including a resistance normally in the ignition circuit for supplying a current sufficient to bring the igniter to incandescency prior to the initiation of the forced draft, and means for cutting out said resistance for increasing the said current sufficiently to maintain the igniter incandescent during the passage of the forced draft thereover.

7. A hot wire ignition device for an electrically actuated forced draft fluid fuel burner mechanism including a constant current transformer in the ignition circuit, an igniter in circuit with the constant current side of the transformer and in the path of

the forced draft, means, including a resistance element normally connected in parallel in the ignition circuit for supplying a current sufficient to bring the igniter to incandescency prior to the initiation of the forced draft, and means for opening the resistance circuit for increasing the said current sufficiently to maintain the igniter incandescent during the passage of the forced draft thereover.

8. A hot wire ignition device for an electrically actuated fluid fuel burner mechanism including a constant current transformer in the ignition circuit, an igniter in circuit with the constant current side of the transformer and in the path of the forced draft, means, including a resistance element normally connected in parallel in the ignition circuit and a normally closed switch in the resistance circuit for supplying a current sufficient to bring the igniter to incandescency prior to the initiation of the forced draft, and means actuated by the initiation of operation of the burner motor to open the resistance switch for increasing the said current sufficiently to maintain the igniter incandescent during the passage of the forced draft thereover.

9. The method of igniting the fuel of an electrically operated and controlled fluid fuel burner mechanism of the forced draft type employing a hot wire ignition device in the path of the fuel and draft consisting in the passing of a current of sufficient strength through the ignition device to heat it to incandescency prior to the supplying of fuel and air under pressure and automatically increasing the strength of the ignition current initiated at the same time with the supply of fuel and air under pressure to maintain the ignition device incandescent and compensate for the cooling effect of the forced draft passing thereover.
